UNITED STATES PATENT OFFICE

AAGE JENSEN, OF EUREKA, CALIFORNIA.

PASTEURIZER.

No. 874,598.

Specification of Letters Patent.

Patented Dec. 24, 1907.

Application filed January 17, 1907. Serial No. 352,729.

To all whom it may concern:

Be it known that I, AAGE JENSEN, a citizen of the United States, residing at Eureka, in the county of Humboldt and State of California, have invented new and useful Improvements in Pasteurizers, of which the following is a specification.

This invention relates to improvements in pasteurizers for pasteurizing milk, cream, 10 and other liquids.

The objects of the invention are to provide a machine of this character, the construction of which is such as to exclude the possibility of any germs commingling with, and contaminating the liquid during the process of pasteurizing; in which the heating medium shall be utilized in the most effective manner possible to accomplish the desired result; and containing means for insuring that the proper 20 temperature is maintained in the heating medium.

In the accompanying drawings, Figure 1 is a vertical section of the apparatus; Fig. 2 is a section on the line 2—2 of Fig. 1; Fig. 3 25 is a broken side view; Fig. 4 is a section on the line 4—4 of Fig. 3; Fig. 5 is detail vertical section of the steam stand pipe.

Referring to the drawings, 1 indicates the outer base section of the machine, supported 30 upon legs 2, and secured by screws 27; on said outer base is an inner or central base section 3, the central portion of which is extended upwards to form a journal 4 for the rotating shaft 5. Said shaft rotates upon an 35 anti-friction disk 6, supported upon a steel disk 7, adjustable by a screw 8 screwed into a step bearing 9 in the end of a bracket 10 secured upon the under side of the base section 1, said bracket having an arm 11 carrying 40 two idlers 12, around which passes a belt 13, which also passes around a driven pulley 14 secured upon the vertical shaft 5 and around a pulley 15 secured on the main shaft 16. Said main shaft is journaled in a bracket 17 45 secured on the outer cylindrical wall 18 of the machine, and reinforced by a plate 19 on the inside of said wall. Thus the main shaft, carrying the loose and tight pulleys, 20, 21, transmits power derived from any distant 50 source, to impart rotation to the vertical shaft 5.

22 indicates grease cups and 23 oiling conduits.

The upper end of the journal 4 is formed 55 with a cup 59 sufficiently large to retain any

oil which should ascend from the oil cavity 60 along the shaft 5, the oil thus accumulating being removed from time to time.

The outer wall 18 of the machine is also the outer wall of the annular chamber 27 for 60 the heating medium. The inner wall 24 of said chamber 27 flares upwards, being soldered at its lower edge to an annular shoulder 28 formed on the inner base 3, and being soldered near its upper edge to a flanged ring 65 25, secured by screws to the outer wall 18. Said inner wall 24 is extended above said ring 25, and is secured to the inner edge of an annular trough 29, said inner edge making in cross section an acute angle with said inner 70 wall 24. The outer side of the trough 29 is formed by a cylindrical vertical wall 30, and within said wall fits a cover 31 open in the center. From one side of said trough 29 extends a horizontal tangential spout or outlet 75 32.

In the conical space contained within the wall 24 of the chamber 27 rotates a conical impeller 26 having a wall formed of sheet metal, secured at its upper edge to an annular shoulder 34 formed on a casting 35 having a hub 36, resting upon a shoulder 37 formed upon the vertical shaft 5, and clamped down upon said shoulder by means of a wing nut 38 screwed upon the threaded end of the 85 shaft. The lower edge of the impeller wall is secured to the lower edge of the bell-shaped base 39 formed at the upper end into a sleeve 40 closely surrounding the shaft 5. Said base 39 is formed with an inwardly and 90 downwardly extending rib 42 upon which is secured an apron 41 extending to within a short distance of the journal 4. On the outside of the impeller are secured longitudinal L-shaped blades 43, which extend close to 95 the inner wall of the heating medium chamber 27. The casting 35 extends horizontally or circumferentially beyond the shoulder 34 close to the vertical wall 30 to form an annular stop plate 44, its function being to hold 100 down the cream, milk or other liquid. From said casting 35, just within the shoulder 34, extends upwardly a circular wall 61, and the inner edge of the cover of the machine fits within close proximity to said wall and thus 105 excludes the entrance of germs.

The liquid to be pasteurized is fed into a bowl 45, from which it flows through a three-way valve 46 to a pipe 47 passing into a chamber 48 formed between the inner base 3 110

and the base 39 but, when the apparatus is in use, the liquid is by centrifugal force immediately drawn up into the narrow annular pasteurizing chamber 49 between the impeller 5 and the inner wall of the heating chamber, and is carried upwards and discharged into the annular trough 29, and passes thence by the horizontal spout 32.

The liquid is by the rotation of the impeller forced against the inner wall 24 of the heating chamber 27, and is thereby heated to the required temperature, its temperature being ascertained by inspection of a thermometer 50 partly inclosed in said chamber. The heating medium generally used is hot water heated by steam admitted by a pipe 51 controlled by a valve 52 and connected by an elbow 54 with a standpipe 53 leading up through the bottom of the chamber 27, and secured in position by locknuts 55 on both sides of said base. From said stand pipe extend, at suitable intervals, nozzles 56, which discharge tangentially and in the opposite direction to the direction of the rotation of the impeller. By means of the jets of steam discharged from the stand pipe in a tangential direction, the water is given a rotary movement, and this has the effect of maintaining the temperature uniform throughout the heating chamber, and also of causing the heat of the water to be abstracted more rapidly by the inner wall 24 of said chamber 27, than if the water were stationary, or circulated only by means of difference of temperatures. These advantages, derived from the rotation of the water, are increased by the fact that said water, on one side of the inner wall 24 of the heating chamber, and the milk, cream or other liquid, on the other side thereof, move in opposite directions. The surplus water arising from the condensation of the steam discharges from an overflow pipe 57.

It will readily be seen that from the time it enters the machine until it leaves it, the liquid to be pasteurized can by no possibility be contaminated with germs, for the apron 41 prevents any of the said liquid passing into the cup 50, and, in the process of being pasteurized, the liquid passes only between the outer continuous wall 26 of the impeller and the inner continuous wall 24 of the heating chamber, and since these are smooth unbroken walls, except for the blades 43, the liquid cannot be contaminated in this part of its movement. When it arrives at the annular trough 29, it is also evidently well protected from contamination, first, by the annular stop plate 44, which extends substantially into contact with the cover, and then by the cover itself, which again extends inwardly into contact with the wall 61 extending upwards from the top of the impeller. Also any hot gas which passes upwards from the heated liquid will pass through the

interstices between said stop plate 44, cover 31 and wall 61 in an outward direction, thus opposing the entrance of any germs into liquid.

A further advantage of this construction is that the whole of the body of the impeller can be removed at any time from the vertical shaft, by merely removing the cover and unscrewing the jam nut, thus the apparatus is easy to keep clean. Any liquid left within the interior cavity of the heating chamber can be readily drained off by means of the valve 46.

I claim:

1. In a pasteurizer, the combination with the upwardly flaring conical inner wall of the chamber for a heating medium, and means for supplying heating fluid to said chamber, of a conical impeller, a vertical shaft, means for rotating the same, a casting secured upon the upper end of said shaft, having an annular shoulder to which the upper edge of the impeller is secured, and a bell shaped base formed at its upper end into a sleeve closely surrounding the shaft, the lower edge of said impeller being secured to said base, substantially as described.

2. In a pasteurizer, the combination with the upwardly flaring conical inner wall of a chamber for a heating medium, of a conical impeller, a vertical shaft, means for rotating the same, a bell shaped base formed at its upper end into a sleeve closely surrounding the shaft, said base having an inwardly and downwardly extending rib, and an apron secured upon said rib, substantially as described.

3. In a pasteurizer, the combination with the upwardly flaring conical inner wall of a chamber for a heating medium, of a conical impeller, means for rotating said impeller within said inner wall, means for supplying heating fluid to said chamber, and means for heating said fluid comprising an apertured stand pipe within the heating chamber, and means for admitting steam to said stand pipe, said apertures opening in the opposite angular direction to that of the impeller, substantially as described.

4. In a pasteurizer, the combination of a heating medium chamber, an impeller rotating within the same, means for rotating said impeller, and means for imparting to the heating fluid in said chamber a rotary motion in the opposite angular direction to that of the impeller, substantially as described.

5. In a pasteurizer, the combination of a heating medium chamber having an inner wall, and a trough connected with the upper edge of said wall, an impeller rotating within said chamber, and comprising a casting at the top thereof, said casting extending circumferentially into close proximity to the outer wall of the trough, and said casting having a circular wall and an annular cover

closing said trough, the inner edge of which extends into close proximity with said circular wall, substantially as described.

6. In a pasteurizer, the combination with
5 a heating medium chamber, of a vertical shaft, a step bearing therefor, a journal for said shaft, an impeller having at the top a casting removably secured on said shaft and at the bottom a base having a sleeve sur-
10 rounding said shaft, and an annular wall connecting said casting and base, and rotating within the inner wall of the heating medium

chamber, said casting having formed therewith a stop plate to form the top of the trough into which the liquid is discharged, 15 substantially as described.

In testimony whereof I have hereunto set my hand in the presence of two subscribing witnesses.

AAGE JENSEN.
